UNITED STATES PATENT OFFICE.

ALLEN E. OSTRANDER, OF RIDGEWOOD, NEW JERSEY, ASSIGNOR TO AMERICAN CAR AND FOUNDRY COMPANY, OF ST. LOUIS, MISSOURI, A CORPORATION OF NEW JERSEY.

CAR-UNDERFRAME.

1,149,400.

Specification of Letters Patent. Patented Aug. 10, 1915.

Continuation in part of application Serial No. 707,592, filed July 3, 1912. This application filed May 5, 1914. Serial No. 836,443.

To all whom it may concern:

Be it known that I, ALLEN E. OSTRANDER, residing at Ridgewood, Bergen county, New Jersey, and being a citizen of the United States, have invented certain new and useful Improvements in Car-Underframes, of which the following is a full, clear, and exact description, such as will enable others skilled in the art to which it appertains to make and use the same, reference being had to the accompanying drawings, which illustrate the preferred form of the invention, though it is to be understood that the invention is not limited to the exact details of construction shown and described, as it is obvious that various modifications thereof will occur to persons skilled in the art.

In said drawings: Figure 1 is a plan view showing the arrangement of the parts of an underframe conforming to the present invention, the floor sheets, transversely extending splice plates, the bolster cover plates and the center sill cover plate, parts of the center sill cover plate being broken away, and the left-hand portion of the underframe of this figure being separated to show the manner of connecting the end portions with the middle portion of said underframe. Fig. 2 is a sectional view, the section being taken on line 2—2 of Fig. 4. Fig. 3 is a longitudinal sectional view, the section being taken in two planes indicated by the line 3—3 of Fig. 4. Fig. 4 is a reproduction on a larger scale of the right-hand end portion of Fig. 1, with parts of the floor plates broken away and with portions of the center sill and side sill arrangement shown in section. Fig. 5 is a side elevational view of the structure shown in Fig. 4. Fig. 6 is an end elevational view of the end sill of a car. Fig. 7 is a vertical sectional view, the section being taken on line 7—7 of Fig. 1, that is at the door opening of the car. Fig. 8 is a similar sectional view, the section being taken at 8—8 of Fig. 1, that is between the door opening and the bolster. Fig. 9 is a sectional view the section being taken on line 8—8 of Fig. 1 through the side wall, with the angle 36 comprising a part of the side sill associated with the side wall 55 riveted to an outstanding flange 56 of a side body post 31. Fig. 10 is a fragmentary elevational view

showing a part of the car at and near the door opening.

55

The form and location of the several parts entering into the car forming the subject-matter of this application will be hereinafter more fully described.

The principal object of the invention is to 60 produce an underframe to be used in box and other cars adapted for use on railroads where it is finally erected, comprising principally commercially rolled members which are easily obtained in the open market for 65 use in the event of repairs, and with the parts entering into the structure so arranged and proportioned that the underframe may be temporarily assembled in the shops of the car builder for inspection, after which 70 it may be separated into a multitude of composite units, which are so arranged that they may be packed for shipment in the holds of 75 seagoing vessels for transportation to the country where the cars are to be used, and for transportation, if necessary, in detached composite units for land shipment to the point of final erection and service.

It is well known that a large number of rivets can be driven either by machine or 80 otherwise in the shop of a manufacturer properly equipped for this service in a more economical manner than such rivets can be driven in the field, or a point remote from the shops of the car builder, where only 85 hand-operated tools are available. In consequence of this, it is one of the objects of the present invention to assemble the composite units in the shops and there drive as many rivets as possible consistent with the 90 subsequent manipulation of the parts or fashioning of the car where it is to be used.

It is practically impossible to load into the hold of a vessel an entire underframe adapted for service on commercial railroads, 95 and where the car parts must be shipped overland prior to the laying of tracks, it is evident that they must be transported in fragments as small as is consistent with the structure to be finally produced. To that 100 end I have designed a car underframe consisting of three major divisions.

Referring particularly to the underframe construction, it will be observed that the center sills 1 are formed of commercially rolled 105 channels, which are spliced to the draft sills

2, which they overlap, by rivets 3 projected through the webs of the center sills and the draft sills. The draft sills are pressed channel sections with their flanges projecting in a direction opposite to that of the center sills, so as to bring the web plates of the draft sills and center sills together, as best shown in the sectional view, Fig. 2.

In transverse alinement with the splice of 10 the center sills and draft sills, the principal side angles 4 and 5 are correspondingly spliced; the angles being riveted together, the connection being established through splice plates 6, as shown in dotted lines at 15 the right-hand side of Fig. 2 and in section in Fig. 4.

The end sections of the underframe consist of the pressed metal draft sills 2, before referred to, angles 5 at the sides and transversely extending end sill angles 7, with which they are associated, other end sill angles 59, secured to, paralleling, and depending from angles 7, body bolsters 8, comprising pressed diaphragms or rolled structural 25 members, or cast members, as may be desired, extending from the center sills and connected with said angles 5, with which are associated diagonal braces 10, which extend from the connection of the bolster with the 30 center sills diagonally outwardly to the corners of the car, all of the members of the end section except angles 59 being united by the floor plates 12, which floor plates are riveted to the inwardly extending flanges 35 of the angle 5, to the top flanges of the draft sills, to the inwardly projecting flanges of the end sill, and to the horizontal flanges of the diagonal brace angles 10. Over the floor above the bolster there is provided a 40 top bolster cover plate 13, which unites the parts of the bolster projecting laterally from the draft sills and serves as a reinforce therefor. The bolster is preferably provided also with a bottom tie plate 14 for well understood purposes.

Between the end sections just described, the central or intermediate portion of the underframe is formed with floor sheets 15 and 16, which extend from the sides of the 50 car toward the center line sufficiently far to overlap the top flanges of the center sills, with which said floor plates are connected by direct rivet connection, which is supplemented by a longitudinally extending center 55 sill cover plate 17, which extends continuously from the rear edge of one bolster cover plate 13 to the corresponding edge of the opposite bolster cover plate 13 at the opposite end of the car, and it is to be noted that the 60 floor plates 15 and 16 and the center sill cover plate 17 serve as an additional means for splicing or connecting the draft sills to the center sills before referred to, as said floor plates and sill cover plate cover the 65 lapping portions of said center sill and draft

sill members 1 and 2. The floor plates at the ends of the middle portion of the underframe overlap the side angles 4 and 5, and serve as an additional reinforce at that connection, this connection or splice being supplemented by the angle plate 6, before referred to.

At convenient points throughout the length of the middle portion of the car, the floor sheets are connected by butt joints; 75 that is, the edge of one sheet abutting the edge of the next sheet just back of the bolsters; that is, at the inner edges of the end plates 12, said plates are connected to the next adjacent plates by means of commercially rolled angles 21. (See Fig. 3). The horizontal legs of these angles are riveted to the floor sheets 15, 16 and 12, and are closely juxtaposed, and the vertical legs of said angles 80 uniting said angles and through said angles 85 uniting the floor sheets before referred to. At other points, if desired, the abutting edges of sheets 15, 15 and 16, 16 may be connected by splice plates overlapping the meeting edges of such floor plates. At still other 90 points, angles 21 may be used singly, instead of in pairs, and be attached by connection angles to the side and center sills to act as floor supports.

In preparing the underframe for shipment it is advisable to divide it for convenience of handling in such a manner that the weight of the parts is as nearly equally distributed as is consistent with subsequent reassembling, and for that reason the draft 100 sills are permanently attached to the bolsters in the shop, said draft sills extending rearwardly of the bolsters, that is toward the middle of the length of the underframe and far enough back to provide a long splice 105 where the center sills lap and are connected thereto.

The bolsters are necessarily heavy, as they form the principal supporting members of the underframe, and it is desirable to connect the end sill and the end portions of the side sills and the draft sills together, hence it is advisable to connect those parts with the bolster by means of the floor plate 12 and top bolster cover plate 13, and ship the 110 fragmentary end portions, such as are shown detached at the left of Fig. 1, by themselves, while the remaining underframe portion, comprising the center sills, center sill cover plate, floor plates intermediate the bolsters 115 and the fragmental side sill portions shown in Fig. 1 as a separate unit.

For the purpose of reinforcing the underframe at the door opening, I have arranged the center floor plates 15^a and 16^a somewhat 125 wider than the plates 15 and 16, said plates 15^a and 16^a extending beyond the side sill angles 4 to form threshold plates, which are stiffened and reinforced within the zone of the door opening by relatively inverted 130

- U-shaped pressings 42, the vertical legs of which are connected by horizontal rivets with the vertical legs of the angles 4, so as to provide proper support for said threshold 5 plate portions of the plates 15^a and 16^a, and the end portions of the parts 42 are connected by angle brackets 44 with side stakes 31, which are commonly used in the body portion of a car.
- 10 As the depending vertical legs of the angles 4 lap the angle 36, it is necessary to provide a filler 47, which extends substantially the length of the underframe, except within the door opening, thereby providing a reinforce for the side sill, which side sill 15 comprises the angles 4 and 36 and said filler plate 47, except at the door opening, where the inverted U-shaped plate 42 takes the place of said filler 47.
- 20 The angle 36 extends continuously, except as hereinafter noted, from end to end of the underframe and, considering the structure herein disclosed, said angle 36 is a necessary part of the underframe as an element of 25 the side sill.
- Where the underframe of the present invention is to be used with a flat car, it would probably be differently divided, but as the underframe of the present invention 30 is intended to be used as a part of a knock-down car comprising the subject-matter of my application for Letters Patent filed July 3, 1912, Serial No. 707,592, I prefer that the angle 36 shall be attached to and be removable with the side wall of such car, and 35 comprises two longitudinally extending sections which abut at the middle of the door opening and are there connected and spliced by means of the inverted U-shaped pressing 40 42, before referred to.
- In addition to the plate 42, the angles 36 are spliced by a supplemental rolled angle 41, shown in section in Fig. 7, which is attached to the vertical and horizontal legs of 45 said angle 36 and extends across and for some distance beyond said door opening.
- What I claim is:
1. In combination, a side sill formed of intermittedlapping and connected parts and 50 a side wall terminating in a rolled member lapping the intermitted portions of said side sill and being connected thereto to connect the same.
  2. In combination, a plural part side sill 55 formed of flanged members having an upper flange inwardly disposed and a body post secured to and connecting said flanged members.
  3. In combination, a plural part side sill

formed of flanged members, a body post secured to and connecting said members, a reinforce member connected to one of said sill members and a floor sheet extending over said sill and said reinforce member.

4. In combination, rolled flanged center 60 sills spaced apart, a bolster, spaced flanged draft sills extending through said bolster lapping said center sills and being secured thereto and a longitudinally extending center sill cover plate riveted to the flanges of 70 said draft sills and center sills within the zone of overlap thereof.

5. In combination, side sills built up of longitudinally lapping and connected flanged members, spaced center sills of flanged 75 members, floor plates connecting said side sills and center sills and center sill cover plates lapping said floor plates and center sills and being riveted to both said floor plates and center sills.

6. In combination, side sills each built up of lapping oppositely disposed angles, rolled flanged center sills, flanged draft sills lapping said center sills, floor plates connected with the upper flanges of said side sills and 85 with flanges of the center sills and longitudinal center sill cover plates lapping and connected to said floor plates.

7. In combination, built up side sills comprising pairs of longitudinally lapping and 90 connected rolled flanged members, a built up end sill, a bolster connecting said side sills, spaced draft sills connected to said end sills and said bolster, a single floor sheet connecting all of said members and spaced center sills lapping and being connected directly with said draft sills.

8. In combination, an underframe part adapted to be shipped as a unit comprising built up side sill parts, a built up end sill, a 100 pair of spaced draft sills and a built up bolster all united by a single floor sheet and a bolster top cover plate riveted to said bolster through said floor sheet.

9. A built up underframe comprising rolled 105 flanged members held in position by floor sheets riveted thereto and comprising built up side sills, in combination with a side wall terminating at its lower side in a rolled flanged member lapping and being connected 110 to said side sill.

In witness whereof I have hereunto set my hand in the presence of two witnesses.

ALLEN E. OSTRANDER.
